(57) **CLAIM**

The ornamental design for a hard drive carrier, as shown and described.

DESCRIPTION

FIG. 1 is a front perspective view of a hard drive carrier, it being understood that the circular and arrow-like design element shown inside the unclaimed rectangular box on the front panel is flat and therefore, only the top surface is being claimed.

The broken lines showing of various regions and the unshaded areas therein are for the purpose of illustrating the article and form no part of the claimed design.
